UNITED STATES PATENT OFFICE.

AXEL E. OSTERBERG AND GUSTAF OBERG, OF NORWAY, MICHIGAN.

TWINE-HOLDER.

1,373,757.

Specification of Letters Patent.

Patented Apr. 5, 1921.

Application filed October 31, 1919. Serial No. 334,706.

To all whom it may concern:

Be it known that we, AXEL E. OSTERBERG and GUSTAF OBERG, citizens of the United States, residing at Norway, in the county of 5 Dickinson, State of Michigan, have invented a new and useful Twine-Holder; and we do hereby declare the following to be a full, clear, and exact description of the invention, such as will enable others skilled in the art 10 to which it appertains to make and use the same.

The invention relates to twine holders and has for its object to provide a twine holder which may be suspended from a ceiling and 15 the free end of the twine allowed to be fed downwardly so as to be at all times within reach of a counter and to provide weight means whereby the free end after being released by the operator at the counter will 20 be raised by means of a weight above the counter thereby preventing the tangling of the string and the further feeding of the same.

A further object is to provide a twine 25 holder of the type that is suspended from the ceiling and wherein the apex of the twine extends upwardly so that the string will feed upwardly to a tubular member thence downwardly through a double chambered extension, one of said chambers having 30 therein a weight through an eye of which weight the string passes, thence passing upwardly and over a roller and thence downwardly through the other chamber 35 having its end disposed below the lower end of the chambered extension. Also to so shape the weight so that it will be prevented from becoming slow in its action by the compression of air within its chamber.

With the above and other objects in view 40 the invention resides in the combination and arrangement of parts as hereinafter set forth, shown in the drawings, described and claimed, it being understood that changes 45 in the precise embodiment of the invention may be made within the scope of what is claimed without departing from the spirit of the invention.

In the drawings:—

50 Figure 1 is a front elevation of the twine holder.

Fig. 2 is a vertical sectional view through the holder.

Fig. 3 is a horizontal sectional view taken 55 on line 3—3 of Fig. 1.

Fig. 4 is a perspective view of the weight.

Fig. 5 is a view of a notched member for placing the string in the holder.

Fig. 6 is a view showing a hooked tool used in threading the holder. 60

Referring to the drawings, the numeral 1 designates the body of the holder, said body having a downwardly extending extension 2 having chambers 3 and 4 therein. Extending horizontally from said body member 65 near its upper end are arms 5 to which arms the arms 6 of the U-shaped supporting member 7 are secured. The U-shaped member 7 is adapted to be supported in a ring 8 which ring may hook over a hook carried by the 70 ceiling of a room or where the ceiling is extremely high a cord or wire may extend downwardly from the ceiling and be secured in the ring 8. The upper ends of the chambers 3 and 4 terminate in a chamber 9, which chamber extends upwardly through the tapered cone holder 10, on which holder the cord cone 11 is adapted to frictionally engage. Extending upwardly from the upper 75 end of the cone holder 10 and in communication with the chamber 9 is a tubular member 12, which tubular member extends above the twine cone and through its upper end. The ball of twine being disposed on the cone holder 10 the twine 13 is then led upwardly and downwardly through the tubular member 12, through the chamber 9 and over a pin 9^a disposed in an opening 9^b so that the corners 9^c and 9^d will form angular bends in the cord thence through the eye 90 14 of a weight 15, which weight is disposed in the chamber 4. The weight 15 is formed with vertically disposed grooves 16 so that as said weight moves upwardly and downwardly the air will be allowed to escape from 95 the chamber 4 thereby preventing the weight from becoming air bound on its downward movement and also preventing the sluggish movement of the weight. The cord after passing through the eye 14 then passes upwardly and over a roller 17 which is disposed between the upper ends of the chambers 3 and 4 there being a transversely disposed pin 18 for preventing displacement of the cord from engagement with the roller 100 17. The cord after passing over the roller 17 passes downwardly through the chamber 3 and thence to a position near the counter or place where the cord is being used. As the cord is used the operator pulls down 105 upon said cord which raises the weight 15 until the weight is raised to a point adjacent

105

the lower end of the opening 9^b thereby taking the angular bend formed by the corners 9^a out of the cord and allowing the cord to feed the ball. However, when the operator 5 finishes wrapping a bundle and breaks the cord and releases the end thereof the weight 15 will move downwardly in the chamber 4 thereby raising the free end of the cord and preventing the same from becoming tangled with other things and consequently becoming unwound and wasted, also preventing further feeding of the cord from the ball.

In placing the cord within the chambers 4 and 5 a tool 19 is inserted in the tubular member 12 and its notched end 20 used for carrying the cord through the chamber 9 where it may be caught up and threaded through the eye 14 of the weight 15 by the tool 21 having a hook 22 on the end thereof. 15 Tool 21 may be inserted through the apertures 9^b in the walls of the downward extending extension 2. However, to facilitate the threading and to allow access to the chambers 3 and 4 the front wall of the 20 downwardly extending extension 2 is provided with a closure 24, hingedly connected as at 25 to the extension 2. Closure 24 may be provided with a rotatable knob 25^a by means of which a lug 26 may be rotated into 25 a channel 27 in the wall between the chambers 3 and 4 thereby holding the closure in closed position.

It will be seen that a twine holder is provided which may be easily suspended from a 35 ceiling and one wherein the cord after being released by the operator will be raised from the counter by means of a weight. It will also be seen that a cord holder is provided wherein the cord and weight is also entirely 40 closed in the holder thereby preventing tangling if the parts of the cord.

The invention having been set forth what is claimed as new and useful is:—

1. A twine holder comprising a body 45 member, said body member having an upwardly extending projection for the reception of a ball of twine, a U-shaped supporting bracket arching the ball of twine for supporting the body member, said body 50 member being provided with a chamber at its upper end, a pair of chambers at its lower end and in communication with the chamber at its upper end, one side of said chambers being open and normally closed 55 by a cover, one of said chambers at its lower end having its lower end closed, a weight

provided with an eye, said weight being disposed in said closed lower chamber and adapted to receive in the eye thereof the twine after it has been passed through the 60 chamber in the upper end of the holder, said weight having vertically disposed grooves for preventing the compression of air within the chamber when said weight lowers, a roller disposed between the upper ends of 65 the chamber and over which the twine passes, the transversely disposed pin for preventing displacement of the twine on the roller, the free end of the twine passing downwardly through the other chamber at 70 the lower end of the body member so that its free end will be disposed below the body member, said weight forming means whereby the free end of the cord will be raised when the cord is released, and a pin disposed in an aperture of the wall of one 75 chamber and into which aperture and over which pin a bight of the cord passes, thereby preventing unwinding of the cord from the ball when the free end of the cord is 80 released.

2. A twine holder comprising a body member, means at the upper end of said body member for holding a ball of twine, a chamber in said body member, the lower 85 end of said chamber being divided into two compartments, a roller centrally disposed in the chamber adjacent the upper ends of the two lower compartments, an aperture in one 90 wall of the chamber and having a transversely disposed pin therein, the cord from said ball being adapted to feed downwardly into the aperture and outside of the pin thereby forming angular bends in the cord, said cord being formed in one of the 95 chambers with a bight, a slidble weight carried by said bight, the free end of the cord passing over the roller and out of the body member through the other chamber, said angular bending of the cord preventing the 100 feeding of said cord until the weight has been raised substantially to the lower angular bend, at which point it will be maintained during the feeding of the cord.

In testimony whereof we have signed our names to this specification in the presence of two subscribing witnesses.
